(57) **CLAIM**

The ornamental design for a jewelry chain, as shown and described.

DESCRIPTION

FIG. 1 is a front elevational view of a first embodiment showing my design;

FIG. 2 is a front elevational view of a second embodiment thereof;

FIG. 3 is a front elevational view of a third embodiment thereof; and,

FIG. 4 is a front elevational view of a fourth embodiment thereof.

The broken line showing of portions of the jewelry chain and gemstones is for illustrative purposes only and forms no part of the claimed design.

1 Claim, 4 Drawing Sheets

FIG. 1

FIG. 2

FIG. 3

FIG. 4
